UNITED STATES PATENT OFFICE

ELMER N. HESSE AND ELMER W. STAHL, OF ROSCOE, NEW YORK

CARD TABLE

Application filed June 5, 1929. Serial No. 368,661.

This invention relates to a table which has its top constructed of a frame covered with composition board, with a covering of cloth or the like on the board, the general object of 5 the invention being to provide means for so attaching the composition board and the covering to the table that the use of nails and the like is rendered unnecessary.

This invention also consists in certain other 10 features of construction and in the combination and arrangement of the several parts, to be hereinafter fully described, illustrated in the accompanying drawings and specifically pointed out in the appended claim.

15 In describing the invention in detail, reference will be had to the accompanying drawings wherein like characters denote like or corresponding parts throughout the several views, and in which:—

20 Figure 1 is a plan view showing a card table constructed in accordance with this invention.

Figure 2 is a section on line 2—2 of Figure 1.

25 Figure 3 is a fragmentary perspective view showing how the groove is formed in the frame.

In these views, the numeral 1 indicates the 30 frame of the table which is composed of four strips having their beveled edges abutting and suitably secured together, such as by the angle clips 2.

35 In carrying out our invention, we form a diagonal groove 3 in each strip of the frame, the groove extending from a point adjacent the inner upper corner downwardly and outwardly through the inner side of the strip, as clearly shown in Figures 2 and 3. The edges 40 of the composition board 4 and its covering 5 are bent downwardly at an angle and placed in the grooves, and if desired, glue or the like may be used to fasten the edges in the grooves. Thus the board with its covering is firmly 45 attached to the frame without the use of nails or the like and the said edges are hidden from view so that the table will present an attractive and neat appearance.

50 It is thought from the foregoing description that the advantages and novel features of the invention will be readily apparent.

It is to be understood that changes may be made in the construction and in the combination and arrangement of the several parts, provided that such changes fall within the 55 scope of the appended claim.

What we claim is:—

A table having its top formed of a frame, the members forming the frame having downwardly diverging grooves removed from 60 their inner edges and opening through the top surface of the frame, and a top forming member having its edges bent correspondingly to the grooves and placed therein, said top forming member consisting of a sheet of composition board and a cover of fabric. 65

In testimony whereof we affix our signatures.

ELMER N. HESSE.
ELMER W. STAHL.
